UNITED STATES PATENT OFFICE.

OTTO A. HOKANSON, OF WOODSTOCK, ILLINOIS, ASSIGNOR TO WOODSTOCK TYPE-WRITER COMPANY, OF WOODSTOCK, ILLINOIS, A CORPORATION OF ILLINOIS.

RIBBON-FEED MECHANISM.

Application filed August 25, 1921. Serial No. 495,332.

To all whom it may concern:

Be it known that I, OTTO A. HOKANSON, a citizen of the United States, residing at Woodstock, in the county of McHenry and 5 State of Illinois, have invented certain new and useful Improvements in Ribbon-Feed Mechanism, of which the following is a specification.

This invention relates to typewriter mechanism for feeding the inking ribbon past the printing point and has for its object the provision of mechanism for this purpose which shall be of improved construction and operation.

10 The invention is exemplified in the combination and arrangement of parts shown in the accompanying drawings and described in the following specification, and it is more particularly pointed out in the appended 15 claims.

In the drawings—

Fig. 1 is a fragmentary top plan view of a portion of a typewriter showing one form of the present invention applied thereto;

20 Fig. 2 is a vertical section of the mechanism shown in Fig. 1 showing one unit of the ribbon feed mechanism in elevation; and

25 Fig. 3 is a vertical section of a typewriter showing the ribbon feed mechanism in front elevation with parts removed.

The present invention is especially applicable to compactible typewriters and in the drawings it is illustrated as applied to a machine of the folding type having a main 30 frame 10 on which is pivotally mounted a pair of folding arms 11 which carry the platen carriage frame 12. The platen carriage 13 is mounted to slide transversely of the machine on ways 14. The arms 11 and 35 the platen carriage frame thereon are arranged to swing forwardly about pivots 15 to bring the platen 16 toward the front of the machine into an inoperative folded position. The ribbon feed mechanism is carried 40 entirely on the main frame so that the folding of the platen carriage does not disturb the operative connection of this mechanism. The ribbon is wound on a pair of spools 17 journaled on horizontally disposed spindles 45 18 which are carried by brackets 19 formed from the side plates of the main frame 10 and bent inwardly from the main frame so that the spools 17 are disposed within the confines of the main frame and are located

55 at opposite sides of the type bars and slightly in front of the platen. This arrangement contributes to the compactness of the device since it utilizes space for the spools which otherwise would not be occupied. The brackets 19 are provided with a bearing 60 sleeve 20 rigidly secured thereto and the spindle 18 is held in place in the bearing sleeve by a collar 21. The ribbon is carried on a removable core 22 which is held in place by a cover 23 and a finger-piece 24, 65 the finger-piece having threaded connection with the spindle 18. The inner flange of the spool 17 comprises a disc 25 fixed to the spindle 18 and provided with ratchet teeth 26 on its periphery. The core 22 is held 70 against rotation relative to the disc 25. Rotation of the ratchet wheel 25 turns the core 22 to wind the ribbon thereon. It will be understood that a spool 17 is provided at each side of the machine and that the ribbon 75 is alternately wound and unwound from each spool.

The ratchet wheel 25 is rotated by a pawl 27 which is pivotally mounted at 28, Fig. 2, on a downwardly extending arm 29 80 connected to a rocking bar 30. The rocker bar 30 is pivotally supported on the side plate of the machine frame 10 at each side of the machine, as shown at 31, and it is provided with a forwardly extending arm 85 32 pivotally connected at 33 with one arm of a bell crank lever 34. The bell crank lever 34 is pivotally supported at 35 on the bracket 19. There is an arm 32 for each end of the bar 30 and each of the bell crank 90 levers 34 is connected by means of a link 36 to a universal bar 37 extending transversely of the machine beneath the key levers 38. Springs 39 normally draw the arms 32 upwardly to rock the bar 30 to 95 its limiting position against stop pins 40. Each time a key lever 38 is depressed the bar 30 will be rocked in a counterclockwise direction, as viewed in Fig. 2, which movement will retract the pawl 27. When the 100 key is released the springs 39 will turn the arms 32 and advance the pawl 27 to feed the ribbon spool in a clockwise direction, as viewed in Fig. 2. A detent 41 is pivotally mounted at 42 on a bracket 43 projecting inwardly from the side plate of the main frame and the pawl 27 and detent 41 are resiliently held in contact with the 105

ratchet teeth 26 by a spring 44. The detent 41 is provided with an upwardly extending arm 45 by means of which the detent and the pawls 27 are moved out of contact with the ratchet teeth 26 when it is desired to reverse the direction of movement of the ribbon. The arms 45 extend upwardly through guide slots 46 in bracket members 47 secured to the inner face of the side plate of the machine frame and projecting inwardly therefrom. The upwardly extending arms 45 are controlled by a cross-bar 48 mounted to slide transversely of the typewriter frame and guided in slots 49 in the bracket member 47. The bar 48 is provided with cam faces 50 in position to cooperate with the arms 45 and swing one of the arms forwardly while the other arm is held in retracted position by its spring 44. The cam faces 50 are provided with notches 51 which retain the arms 45 in their foremost position, thus holding the pawls connected therewith out of operative relation with the corresponding ratchet teeth 26.

The position of the ribbon reverse bar 48 is shifted to reverse the direction of ribbon feed each time the ribbon is completely unwound from one of the spools. The bar 48 is shifted by bell crank levers pivoted at 52 on the brackets 47. These bell crank levers are provided with arms 53 which engage pins 54 on the bar 48. The arms 55 of the bell crank levers carry rocker levers 56 pivoted at 57 on the arms 55. The forward ends of the levers 56 are bent to form contact bars 58 normally disposed in the path of arms 59 on bell crank levers 60 pivoted at 61 on the side wall of the main frame 10. The arm 59 is provided with an offset portion 62 to bring the end of the arm into position to engage the contact bar 58. The bell crank lever 60 is provided with an upwardly and forwardly extending arm 63 which carries a roller 64 at its end in position to rest on the ribbon wound upon the spool 17. The core 22 of the spool 17 is provided with a notch 65 into which the roller 64 drops when the ribbon is completely unwound from the spool. This movement of the roller 64 will cause the arm 59 to swing the lever 56 from its broken line to its full line position shown in Fig. 2. The lever 56 is normally held in the broken line position by a spring 66. The end of the lever 56 opposite the contact bar 58 is provided with a cam plate 67 which moves downwardly when the lever is swung to the full line position in Fig. 2. This will bring the cam plate 67 into the path of an upwardly extending arm 68 secured to the rocker bar 30. It will be apparent that the arm 68 will move forwardly each time the bar 38 is oscillated by the depression of a key lever. So long as the roller

64 is supported on the ribbon wound upon the spool 17, the oscillation of the arm 68 will not affect the cam plate 67 but when the roller 64 drops into the notch 65 the cam plate 67 will be brought into the full line position shown in Fig. 2, so that the next depression of a key lever will cause the arm 68 to engage the rear edge of the cam plate 67 and swing the cam plate to the left, as viewed at the right-hand side in Fig. 1. This will move the bell crank arms 53 and 55 about the pivot 52 in a counterclockwise direction, as viewed in that figure, and shift the bar 48 to the left releasing the lever 45 from the notch 51 and permitting it to move rearwardly under the tension of the spring 44 to bring the detent 41 and the pawl 27 into engagement with the ratchet teeth 26. At the same time the cam face 50 at the opposite side of the typewriter will press the lever 45 at that side forwardly and release the pawls from the ribbon spool ratchet. In this way the direction of the ribbon feed will be reversed and the ribbon will be rewound upon the spool which has just been emptied.

The detent 41 is provided with a pin 69 which projects through an opening in the pawl 27 to retain the pawl and detent in proper relation to one another at all times. An arm 70 is pivoted at 71 on the rear portion of the machine frame and engages a notch 72 in the edge of the bar 48. A spring 73 is secured to the frame of the machine directly below the pivot point 71 so that the arm and spring serve to throw the bar 48 to its extreme position in one direction or the other as soon as it has past the central position in its range of movement. The ribbon extends upwardly from the spools 17 and passes through loops 74 carried by arms 75 supported on a shaft or bar 76 which is pivotally mounted in the side walls of the frame. The ribbon extends from one loop 74 to the other in front of the platen 16 in position to be struck by the type bars. Any suitable guide for the ribbon may be provided at the printing point, such guide being carried by an arm 77 also secured to the rod 76. When the platen carriage is moved to its folded position the guides 75 and 77 swing forwardly so that they will not extend above the upper edge of the machine frame. The rod 76 may be provided with a rearwardly extending arm 78 which engages a slot in a bar 79 slidably mounted on the rear of the machine frame. The bar 79 projects upwardly in position to engage the lower surface of the carriage frame 12 when the frame is moved to its operating position. The carriage frame will force the bar 79 downwardly and rotate the rod 76 in a clockwise direction, as viewed in Fig. 2, thus automatically restoring the ribbon guide to its operative position after the

platen has passed the position where it would strike the guide if the guide were already raised.

The type bars 80 are pivoted on a type bar segment 81 carried by the rear portion of the machine frame and are connected by links 82 to sub-levers 83 which are operated by the key levers 38. It will be noted that the ribbon spools 17 occupy positions at opposite sides of the tape bar basket, but within the confines of the machine frame, thus providing a very compact construction and permitting the machine to fold into a small space when not in use.

15 I claim:

1. In a compactible typewriter, a main frame, a platen carriage frame pivotally mounted thereon for movement into and out of operating position, a ribbon guide on said main frame arranged to project into position to guide a ribbon adjacent said platen, said guide being foldable into compacted position, and means for automatically moving said guide into operating position 25 when said platen carriage frame is moved into its operating position.

2. In a compactible typewriter, a main frame a platen carriage frame pivotally mounted on said main frame for movement into and out of operating position, ribbon spools carried by said main frame, ribbon feed mechanism carried by said main frame for operating said spools, a ribbon guide mounted on said main frame and movable into and out of the path of said platen carriage frame, said guide being foldable into compacted position when said platen carriage is folded, and means for automatically moving said guide into operating 35 position when said platen carriage frame is moved to its operating position, and after said platen carriage has moved past the point in its path of travel into which said guide projects when in operating position.

40 3. In a typewriter, a supporting frame, a pair of ribbon spools mounted on said frame, pawl and ratchet mechanism for each of said spools, levers for disconnecting said pawl and ratchet mechanisms, a bar slidably transversely of said typewriter and having means thereon for actuating said levers when said bar is slid to disconnect the pawl and ratchet mechanism of one of said spools when the mechanism of the other spool is 45 connected, key lever operated means for actuating said bar, followers arranged to engage the ribbon on said spools, and means controlled by said followers for bringing said key lever operated means into position 50 to actuate said bar and effect a reversal of the pawl and ratchet mechanism whenever the ribbon is completely unwound from either one of said spools.

45 4. In combination with the key levers of a typewriter, of a member oscillated at each

operation of the key levers, ribbon feeding mechanism, mechanism for reversing said ribbon feeding mechanism comprising a sliding bar, a pivoted lever having pivotal connection with said sliding bar for operating said reversing mechanism, said lever having a pivoted member thereon movable into and out of the path of said oscillating member so that said pivoted member is engaged by said oscillating member to operate said lever and reverse said feeding mechanism whenever said pivoted member is moved into the path of said oscillating member, and means controlled by the ribbon for moving said pivoted member into the path 70 of said oscillating member when it is desired to reverse the ribbon feeding mechanism.

5. A typewriter comprising a main frame, a spool mounted on a horizontal axis on said frame, a follower mounted on a horizontal 75 pivot and arranged to rest upon the ribbon on said spool, a bell crank lever arranged to swing in a horizontal plane, a key actuated oscillating member, a vertically swinging contact piece carried by said bell crank 80 lever, means actuated by said follower for swinging said contact piece into the path of said oscillating member when the ribbon is unwound from said spool, mechanism for rotating said spool to feed the ribbon carried thereby, and means actuated by said bell crank lever for reversing the direction 85 of operation of said feeding means.

6. A typewriter comprising a main frame, a platen carriage frame pivotally 100 mounted on said main frame and having supporting arms positioned at opposite sides of said main frame, ribbon mechanism mounted on said main frame and comprising a pair of ribbon spools journaled on 105 horizontal axes, said spools being positioned adjacent said supporting arms at opposite sides of said main frame, and a pair of ribbon supports arranged one adjacent each of said ribbon spools, said supports being foldably mounted on said main frame and having guides thereon in alinement with the peripheries of said ribbon spools to direct the ribbon from said spools across said typewriter substantially parallel with said 110 platen carriage support.

7. A typewriter comprising a main frame, a platen carriage frame having arms pivoted to said main frame and arranged adjacent the sides thereof, ribbon spools journaled on horizontal axes at opposite sides of said main frame and adjacent the inner sides of said foldable arms, a bar extending transversely of said main frame, and a pair of spaced ribbon guides mounted on said bar 125 and foldable forwardly into compact position.

8. A typewriter comprising a main frame, a platen carriage frame movably mounted on said main frame, a platen movable on 130

- said platen carriage frame and extending transversely of said main frame, ribbon spools journaled on horizontal axes at opposite sides of said main frame, said spools having core members provided with peripheral recesses, a follower pivoted adjacent each of said spools and having a contact member arranged to bear upon the ribbon wound upon said spool, pawl and ratchet mechanism for operating each of said spools, a lever pivoted adjacent each spool for disengaging the pawl and ratchet mechanism therefor, a transversely extending bar for controlling both of said levers, a pivoted member adjacent each of said spools for shifting said bar, a contact device pivotally mounted on each of said pivoted members, key lever actuated means for engaging said contact devices, and means controlled by said followers for moving the contacting devices of the respective spools into the path of said key lever actuated means when the ribbon is unwound from a spool.
- In testimony whereof I have signed my name to this specification on this 22nd day 25 of August, A. D. 1921.

OTTO A. HOKANSON.
